SET-UP CONTAINER

Samuel N. Lebold and Henry K. Powell, Chicago,
Ill., assignors to Morris Paper Mills, Chicago,
Ill., a corporation of Illinois

Application August 10, 1936, Serial No. 95,062

6 Claims. (Cl. 229—5.7)

Our invention relates to containers for the packing or packaging of commodities, and pertains particularly to containers of the type which may be manufactured and shipped in a knocked-down or substantially flat condition and may be set up at the point of use. It finds particular utility in containers of substantial size, for example, containers of two and one-half or five-gallon capacity for the packaging of ice cream. The present 5 application is a continuation in part of our co-pending application Serial No. 644,809 filed November 29, 1932.

A general object of the invention is to provide an improved construction for a collapsible or 10 knock-down container which may be made for the most part of paper board or the like, and which may be manufactured and shipped in a substantially flat knocked-down condition and may be set up easily and quickly at the point of 15 use to form a strong and accurately sized container which will suitably retain and protect its contents and which will be capable of withstanding the usage to which bulky packages of ice cream or the like are subjected in transportation.

20 A particular object of the invention is the provision of an improved construction for such a container which is particularly adaptable for the freezing within it of a content of ice cream or other material which expands upon freezing, the 25 container being qualified to accommodate expansion of its contents, and the joints or connections between the separately formed portions of the container being tightened and rendered additionally secure incident to such expansion of the contents.

Still another object is the provision of an improved container construction of the type above specified which may be made for the most part of inexpensive material, such as paper board or 30 the like, and in which the margins of the several connected paper board parts, and the joints therebetween, are effectively protected against external abrasion and wetting by simple and inexpensive elements which also perform the functions of securing the parts together and maintaining the container in the desired cross-sectional 35 form.

Other and further objects of the invention will be pointed out or indicated hereinafter or will be 40 apparent to one skilled in the art upon an understanding of the invention or its employment in use.

For the purpose of facilitating an explanation of the invention, we show in the accompanying 45 drawing forming a part of this specification and

hereinafter described, certain structural embodiments of it and various detailed features. It is to be understood, however, that these are presented merely for purpose of illustration and hence are not to be interpreted in any manner calculated to limit the appended claims short of the true and most comprehensive scope of the 5 invention in the art.

In said drawing:

Fig. 1 is a perspective view of a tubular body 10 member of a sort suitable for use as a part of our improved container;

Fig. 2 is a cross-sectional view of a portion of such body member;

Fig. 3 is a broken sectional elevational view of 15 the upper portion of a container embodying the invention, same showing the parts in their set-up or assembled relationship;

Fig. 4 is a broken sectional elevational view of 20 the lower portion of such a container, the parts being shown in their set-up or assembled relationship;

Fig. 5 is a detail in the nature of a part sectional elevational view of a modified form of construction for the lower end of the container; and 25

Fig. 6 is a similar detail of a second modified form of construction for the lower end of the container.

The packing of ice cream in bulk, viz., two and one-half and five-gallon packages, requires a container which, in addition to being leak-proof, is of very substantial strength, in order to withstand the usage to which it is subjected in packing, shipment and dispensing of the contents, and which is well qualified to prevent softening or weakening 30 by wetting. When it is intended that the container be discarded after a single use, rather than returned for re-use by the packer, it is quite essential that it be of a character such that it may be supplied to the packer at very low cost. The 35 cost involved in packaging, shipment and storage of containers prior to use may be minimized by supplying them to the packer in knocked down condition. The provision of a suitable construction for a container which can thus be supplied to the user in knocked down condition and set up by him quickly and with facility and which will possess the other essential characteristics of tightness, strength and durability, has presented a matter of considerable difficulty, particularly in 40 view of the necessity of keeping the cost of the container very low. The present invention provides a container which meets all of these exacting requirements.

The nature of the invention will be most quick- 45

ly ascertained from the following detailed description of the illustrative embodiments shown in the drawing.

The constructions here shown are designed to be made of quite light and inexpensive materials, and include a tubular body member 10 which constitutes the side walls of the container. Such body member may be made of sheet material in the nature of paper board of a thickness more or less approximating .045 of an inch. One form of sheet structure which may be employed is illustrated in Fig. 2, same comprising a chip center portion 10a, liner sheet 10b and kraft outer sheet 10c, all secured together by suitable adhesive as in customary converting practice. It will be appreciated that the board need not necessarily be of this particular structure, or that it be of laminated structure as here shown. It is important, however, that the body member be flexible circumferentially and possess substantial rigidity longitudinally and that the board of which it is made possess requisite toughness. In order to permit collapsing of the body member, it is provided with longitudinal creases constituting fold lines 11, which allow the tubular body member to be compressed or collapsed into substantially flattened form.

It is also desirable to form the body member with flexing creases or slightly offset portions 12, which extend in the longitudinal, or top to bottom direction, and are spaced from one another by appropriate intervals. In such creasing or offsetting of the board, the material is not distorted to such an extent as to shear or break the fibers, but the offset is sufficient to striate the board by forming shallow grooves on one side thereof and low ridges on the other. It will be understood that these creases or striations may be pressed in the board in various fashions and in various forms and relationships. They facilitate the shaping or conformation of the body member to the desired form or contour when the container is set up. An application of suitable waterproofing material such as paraffin, may be made to the surfaces of the board, the same preferably being ironed in so as to avoid any appreciable coating which might be scraped off.

As closures for the ends of the tubular body member, we provide a top closure disk 14 and a bottom closure disk 15 preferably made of stiff paper board and of circular contour, the upper closure disk 14 being of a size such as to overlap the upper end margin of the body member when the latter is set up in approximately cylindrical form. The bottom closure disk 15 is of a diameter slightly greater than the normal internal diameter of the body member when the latter is set up in approximately cylindrical form, but it nevertheless is of such size as to permit its being forced into the tubular body member to a position normal thereto.

For assembly with the body member and the bottom closure disk, there is provided a relatively non-distensible constraining member 16 of annular form which is made of a suitable durable and relatively rigid material, preferably sheet metal. It has a hoop-like portion 16a adapted to encompass the lower end portion of the body member, and an inwardly extending flange portion 16b which is adapted to extend inwardly across the end margin of the body member. The inner margin of the flange 16b may be turned upwardly as illustrated at 16c. The hoop portion 16a is provided, at circumferentially spaced intervals, with inwardly projecting body-engaging members

16d. If the constraining member 16 is made of sheet metal, the members 16d may be formed as inwardly punched burrs or punch pricks.

In assembling the container from the knocked-down or collapsed form, the body member is opened or distended to a tubular form, and one end inserted within the hoop portion 16a until its lower margin abuts the flange 16b. The bottom closure disk is then forced down within the body member, past the body engaging member 16d, until it seats upon the inner portion 16c of the bottom flange. The flexing creases or offset portions 12 facilitate the shaping of the body member to the annular contour of the hoop portion 16a, and they also facilitate the circumferential distension of the body member necessary to accommodate the slightly oversized bottom closure disk 15. Thus the lower end portion of the body member is enabled to fit tightly against the inner surface of the hoop portion 16a and, with the forcing of the bottom closure disk 15 past the body engaging member 16d into its seated position in normal relationship to the body member, the body-engaging members 16d are caused to bite into the outer portion of the body member board. The bottom closure disk 15 holds the lower end portion of the body member in tight binding engagement with the hoop portion 16a and in inter-engagement with the body-engaging member 16d, and by virtue of its tight binding fit against the inner surface of the body member, the bottom closure disk forms a tight bottom for the container.

For assembly with the top closure disk 14 and the upper end portion of the body member we provide a constraining member 17 formed with an annular hoop-like portion 17a adapted to encompass the upper end portion of the body member, and an inwardly turned flange or bead portion 17b which is sufficiently wide to extend across the upper end margin of the body member, and which preferably has its inner margin turned downwardly as shown. The constraining member 17 is made of a suitable durable and relatively rigid material, preferably sheet metal, and its hoop portion 17a is provided, at circumferentially spaced intervals, with inwardly extending body-engaging members 17c which, if the constraining member is made of metal, may be formed as inwardly punched burrs or punch pricks.

In the use of the container for the packing of ice cream or the like, the body member is assembled with the lower constraining member 16 and bottom end closure member 15 as above described. This provides a tight receptacle which is open at its top and adapted to receive the material to be packaged. This, in the case of ice cream or sherbets, is customarily placed in the container in liquid, or partially frozen, semi-liquid, form. Then, the top closure member 14 having been placed in the constraining member 17 and seated against the flange 17b, the hoop portion 17a of the constraining member is telescoped onto the upper end portion of the body member and pressed down until the disk 14 is seated upon the upper edge of the latter.

The closed package is then submitted to freezing treatment, as in a freezing room. With the expansion of the contents which results from the freezing thereof, outward pressure will be exerted upon the body member, and this will have the effect of somewhat distending the latter. Such distention is accommodated or facilitated by the pliability of the board of which the body member is formed and by the provision of the creases

12, the material in the striae or offset portions being susceptible of displacement radially as the body member is drawn taut in approximately circular peripheral contour. Incident to such dis-
 5 tention of the upper portion of the body member which is encompassed by the constraining mem-
 ber 17, the outer surface of the board will be pressed into tight binding engagement with the hoop portion 17a and the body-engaging members
 10 17c will be caused to bite into or inter-engage with the outer portion of the body member board. Accordingly, when the contents of the container is congealed or frozen, the upper constraining member 17, as well as the lower constraining member 16 will be held securely interengaged with the body member and the end closures held
 15 tightly in place.

With the form of bottom constraining member 16 illustrated in Fig. 4, the upwardly turned marginal portion 16c spaces the bottom closure disk 15 slightly above the lower edge of the body member. In the modified construction shown in Fig. 6 the constraining member is designated by the reference numeral 16' and its bottom 20 flange is not turned upwardly at its inner edge. With this form of constraining member, the body member 10 may be inserted as above described until its lower edge abuts the bottom flange of the constraining member, or an additional paper board disk 18, of such diameter as to fit within the hoop portion of the constraining member, may first be seated on the bottom flange of the constraining member, and the body member 10 then inserted until its end portion 25 abuts the disk 18, the end closure disk 15 then being inserted within the body member in the manner and with the results above described.

In the modified construction illustrated in Fig. 5, the bottom constraining member 16 is of the form first above described, but the body member 10 has its lower marginal portion 19 folded over against its outer surface and fastened thereto by adhesive to form a peripheral ledge adapted to engage under the body-engaging members 16d when the lower portion of the body member is positioned within the constraining member and in abutment with the bottom flange 16b. The bottom closure disk 15 holds the lower end portion of the body member distended in close binding engagement with the hoop portion of the constraining member and the body-engaging members 16d cooperate with the peripheral ledge to prevent withdrawal of the body member from the constraining member. It is to be noted that the upper end portion of the body member may be likewise formed with a peripheral ledge for cooperation with the body-engaging members of the upper constraining member 17 as a means for retaining the top closure in place on the body member.

It is desirable that the body-engaging mem-
 65 ber or elements 16d and 17c be of such size and form as to have a secure purchase or engagement with the body member, but not as to pierce the entire thickness of the body member board when the body member is retained under constraint by the hoop-like portion. The flexibility of the body member in radial directions permits insertion of its end portions past the body-engaging elements, such flexibility being contributed in part by the longitudinal creasings 11 and 12.

To facilitate opening of the container, the top closure disk 14 may be formed so as to be cut, broken or torn out and completely removed from
 75 the upper constraining member 17, leaving the

latter securely retained on the body member to reinforce and protect its upper end and hold it in circular form.

The construction above described provides a container which may be manufactured and supplied to the user at very low cost, and which possesses the advantages of strength, durability, collapsibility and facility of assembly.

We claim:

1. A knock-down container comprising a tubu-
 lar body member made of paper board and adapt-
 ed to be collapsed to flattened knocked-down
 form and to be set up in approximately cylindri-
 cal form, said body member being circumferen-
 tially expansible when in its cylindrical form, an
 10 end closure disk for closing the end of the tubular
 body member, and a substantially rigid annular
 constraining member adapted to be telescoped
 onto an end portion of the tubular body member,
 said constraining member having a hoop-like 15
 portion adapted to encompass the closure disk
 and an end portion of the tubular body member
 and an inwardly extending flange portion adapt-
 ed to overlap the outer face portion of the clo-
 sure disk, said constraining member being pre-
 20 formed with inwardly projecting body-engaging
 elements spaced from one another circumferen-
 tially thereof and adapted to engage in peripheral
 portions of the tubular body member when said
 25 end portion is expanded into peripheral engage-
 ment with the hoop-like portion.

2. A knock-down container comprising a tubu-
 lar body member made of paper board and adapt-
 ed to be collapsed to flattened knock-down form
 and to be set up in approximately cylindrical
 30 form, said body member being circumferentially
 distensible when in its cylindrical form, a sub-
 stantially rigid annular constraining member
 having a hoop-like portion adapted to be tele-
 scoped onto an end portion of the tubular body 35
 member when the latter is set up, said annular
 constraining member having an inwardly extend-
 ing flange portion adapted to project across the
 end edge of the tubular body member, said hoop-
 like portion being pre-formed with inwardly pro-
 jecting body-engaging elements spaced from one
 40 another circumferentially thereof and adapted
 to engage in peripheral portions of the tubular
 body member upon circumferential distension
 thereof, and a disk adapted to be inserted within
 45 the tubular body member to hold peripheral por-
 tions thereof distended in engagement with the
 body-engaging elements.

3. A knock-down container comprising a tubu-
 lar body member made of paper board and adapt-
 ed to be collapsed to flattened knocked-down form
 and to be set up in approximately cylindrical
 50 form, said body member having a circumferen-
 tially distensible end portion, a closure disk
 adapted for assembly with an end of the body
 member, and a relatively rigid annular constraining
 member having a hoop-like portion adapted
 55 to be telescoped onto said distensible end portion
 of the body member and an inwardly projecting
 flange portion adapted to extend across the end
 edge of the body member, said constraining mem-
 ber having pre-formed body-engaging elements
 60 projecting inwardly and spaced from one another
 circumferentially thereof and adapted to engage
 in peripheral surface portions of said end portion
 of the body member when it is distended within
 65 the hoop-like portion.

4. A knock-down container comprising a tubu-
 lar body member made of paper board and adapt-
 ed to be collapsed to flattened knocked-down 70
 75

- form and set up in approximately cylindrical form, said body member having a circumferentially distensible end portion, a relatively rigid annular constraining member having a hoop-like portion adapted to be telescoped onto said end of the body member when it is set up, said constraining member having pre-formed body-engaging elements projecting inwardly spaced from one another circumferentially thereof and adapted to engage in peripheral surface portions of the body member, and a disk adapted to be inserted within the body member to hold said end portion distended in engagement with said body-engaging elements.
15. 5. In a container having a tubular body member made of paper board and adapted to be collapsed to flattened knocked-down form and set up in approximately cylindrical form and having an outwardly distensible end portion, a relatively non-distensible constraining member for holding an end closure assembled on said body member, said constraining member having a hoop-like portion adapted to be telescoped onto said end portion of the body member and being provided with inwardly projecting body-engag-

ing elements spaced from one another circumferentially thereof and formed to be intruded into peripheral portions of the body member, said hoop-like portion cooperating with the body member to prevent intrusion of the body-engaging elements entirely through the body member board. 5

6. A container comprising a tubular body member made of paper board and adapted to be collapsed to flattened knocked-down form and set up in approximately cylindrical form, said body member having a distensible end portion provided with a peripheral ledge, an end closure for said body member comprising an end disk and a relatively non-distensible annular constraining member having a hoop-like portion adapted to be telescoped onto said end of the body member in encompassing relation to said ledge, said hoop-like portion being provided with inwardly projecting body-engaging elements 20 spaced from one another circumferentially thereof and adapted for engagement with said ledge to retain the end closure on the body member. 15
